MONORAIL CONVEYER AND CHAIN
THEREFOR

Arthur S. Hamilton, Jr., Brighton, N. Y.

Application March 12, 1947, Serial No. 734,023

1 Claim. (Cl. 198—177)

1 This invention relates to an endless conveyor of the type in which a multiplicity of work-supporting trolleys are connected to an endless chain or the like for traveling at uniform distances apart on a monorail, and it has for its purpose to afford a low cost construction enabling the use of welded coil chains, or chains composed of links of integral loop formation and arranged between adjacent trolleys.

In monorail conveyors as heretofore constructed, the practice has been to employ a machine or forged chain coextensive with the rail or track and having trolleys secured thereto at uniform distances apart, or a cable coextensive with the rail and extending successively through the several trolleys which are fastened thereto at uniformly spaced distances, and it is a particular object of the invention to reduce the cost of manufacture and to simplify attachment of the trolleys by using forged or welded coil chains or chains composed of integral links of loop formation and to attach such chains fabricated to uniform length between adjacent trolleys and thus establish uniform distancing between trolleys without the necessity of fastening the trolleys to a continuous chain or cable.

Another purpose of the invention is to provide a trolley structure that utilizes chains that are stretched to a uniform length, and to provide means for readily attaching such chains to the trolleys.

A further object of the invention is to afford an economical and practical form of trolley constructed to permit readily attaching a chain at either end or quickly removing it when necessary.

An additional purpose of the invention is to provide a trolley of integral formation having no movable parts and which is both strong and durable, which enables quickly attaching a chain to both ends, and securely holds the chains when in operative position so as effectively to prevent their unintentional or accidental removal.

To these and other ends, the invention consists in the construction and arrangement of parts that will appear clearly from the following description when read in conjunction with the accompanying drawings, the novel features being pointed out in the claim following the specification.

In the drawings:

Fig. 1 is a view in side elevation partially broken away showing a preferred embodiment of the invention as applied to a monorail conveyor, and illustrating a multiplicity of work-support-

2 ing trolleys connected by separate chains of uniform length;

Fig. 2 is a side elevation of one of the trolleys;

Fig. 3 is a view in end elevation of the same;

Fig. 4 is a vertical sectional view, partially in elevation, on line 4—4 of Fig. 2 looking in the direction indicated;

Fig. 5 is a horizontal sectional view on the line 5—5 of Fig. 2 looking in the direction indicated, and

Fig. 6 is a detail view in side elevation partially broken away, showing a section of the chain employed.

Referring more particularly to the drawings in which like reference numerals refer to the same parts throughout the several views, the illustrated embodiment of the invention includes a fixed rail or track 1 upon which the work-supporting trolleys designated generally at 2 travel, being propelled by suitable operating mechanism as usual in the art and which forms no part of the present invention, while 3 designate the welded coil chains formed of integral loop-shaped links, or links of other shape of integral or welded formation and extending through adjacent links.

The links of such chains vary somewhat in size and length and the chains which connect adjacent trolleys are made of substantially uniform length by stretching each chain unit composed of a given number of links to the standard length desired, and the separate chains thus formed are individually secured between adjacent trolleys which are constructed to permit quick attachment, or removal when a chain is to be replaced, each trolley being constructed for this purpose in the following manner.

The trolley indicated at 2 includes pintles 4 at the top on which the trolley wheels 5 are mounted for supporting the trolley on the track 1, and a bifurcated portion 6 at the bottom having openings 7 to receive a pin on which the work carrier 8 is mounted, and in order to enable quickly attaching the connecting chains to the trolley, the latter is provided at each end with means for detachably receiving the end link of a chain and for locking such link in place after its assembly. The fastening means at the two ends of the trolley are oppositely disposed or extend in opposite directions transversely of the trolley, as will appear more clearly hereinafter, and it will therefore be necessary to describe in detail only one of the fastening devices.

At either end, the trolley includes a vertical side wall 9, while 9 designates a post formed in-

tegral with the vertical wall 8 and extending laterally therefrom at a point approximately intermediate the top and bottom edges of the vertical wall 8. The post 9 is provided at its outer end with an integral elongated locking portion 11 which lies in a plane parallel to the side wall 8 and is inclined to a vertical plane perpendicular to the side wall as shown. The locking portion 11 is of a width slightly less than the width of the opening in the end link of the chain, as for example, the chain link may be provided with an opening $1\frac{1}{64}$ " in width and the locking portion would have a width of $1\frac{1}{64}$ " enabling it to pass through the end link of the chain. The locking portion is of slightly greater length than the length of the opening in the link of the chain and extends above and below the post 9 preferably a greater distance above the post than below, and the chain is attached by positioning one end of the connecting link over the lower end of the locking portion 11 and then by drawing the link upwardly under the locking portion 11, until the upper end of the link clears the upper end of the locking portion, the link can be moved inwardly over the locking portion and is then free to swing to a horizontal position around the post 9 and behind the locking portion 11.

Accidental removal of the connecting link from the post 9 is prevented by a vertically inclined transverse wall 12 spaced from and parallel to the locking portion 11, while 13 designates a horizontal bottom wall spaced from and beneath the locking portion 11, and 14 designates a curved wall spaced from the lower end of the locking portion 11 and connecting the vertically inclined and horizontal bottom walls 12 and 13 respectively. The walls 12, 13 and 14 are spaced from the locking portion sufficiently to permit the end link of a chain to be inserted around the locking portion 11 and between it and the surrounding walls for attaching, and after the link is behind the locking portion 11 and drops to horizontal position, it rests above the horizontal bottom wall 13 in engagement with the post 9, and in this position, the walls 12, 13 and 14 effectively prevent sufficient movement of the link to permit its removal over the locking portion 11.

To engage or disengage a chain with a trolley, it is necessary to position the connecting link at an inclination to the horizontal and to the next link of the chain in line with the locking portion 11 so that it can be inserted thereover, and at the same time it is necessary to swing the trolley slightly so that the end being connected is tipped slightly downwardly away from the track on which it moves, such tipping movement of the trolley being sufficient to permit the end link of the chain to be moved upwardly far enough so that it can be pushed laterally over the upper end of the locking portion 11 and then swung downwardly behind the locking portion to horizontal position, resting above the bottom wall 13 and engaged with the post 9. In order to facilitate attachment and removal of the connecting chains and to provide a balanced structure, the vertical wall 8, connecting post 9 and correlated parts are in reversed position transversely at the two ends of the trolley as shown.

With the arrangement described, it is possible to employ a welded coil chain, or a chain composed of integral loop-shaped links, involving a much more economical structure than a machine or forged chain and to secure the separate chains to adjacent trolleys so that the trolleys of a conveyor are uniformly and equally spaced as required for the driving instrumentalities of such an endless conveyor, and the invention also permits of quickly attaching the opposite ends of such a chain to adjacent trolleys or easily removing them from the trolleys when necessary for replacement, servicing, or repair, and while in operative position, the chains are securely fastened to the trolleys and effectually held against accidental or unintentional removal so that the conveyor has the same degree of efficiency as one employing an endless machine chain or cable, while the cost of production is greatly reduced and the time required for removing or replacing any part of a chain or a trolley is considerably lessened.

While the invention has been described with relation to the particular structural embodiment herein shown, it is not restricted to the details disclosed, and this application is intended to cover such changes or departures as may come within the purposes of the improvement or the scope of the following claim.

I claim:

In an endless conveyor, the combination with a track and a series of work-supporting trolleys movable thereon and spaced from each other, of separate chains of substantially uniform length connecting adjacent trolleys, interlocking means on each trolley engaged with the chains connected thereto and including vertical side walls, posts extending laterally from said vertical side walls, an elongated locking portion integral with each post and extending perpendicularly thereto at the outer end of the post, said locking portion being inclined and extending a greater distance above the post than below, an inclined transverse wall parallel to and spaced from said locking portion, a horizontal bottom wall beneath said locking portion and spaced therefrom, and a curved wall connecting said bottom and transverse walls and extending around the lower end of said locking portion in spaced relation thereto.
